UNITED STATES PATENT OFFICE.

BERNARD M. MCFARLANE, OF HETTINGER, NORTH DAKOTA.

BINDER ELEVATOR.

Application filed October 30, 1919. Serial No. 334,439.

To all whom it may concern:

Be it known that I, BERNARD M. MCFARLANE, a citizen of the United States, residing at Hettinger, in the county of Adams, State 5 of North Dakota, have invented certain new and useful Improvements in Binder Elevators; and I do hereby declare the following to be a full, clear, and exact description of the invention, such as will enable others 10 skilled in the art to which it appertains to make and use the same.

This invention relates to grain binders, and more especially to that class of devices known as endless belt loaders; and the object of the same is to produce a simple form 15 of elevator mechanism which can be applied to the binder by first removing certain parts of the latter, and is serviceable for carrying grain from the table of the 20 binder to the header box.

The invention includes an elevator consisting of an ordinary endless canvas belt or 25 apron with slats, but it has specially constructed sides and top for holding the grain in place on the upper stretch of the apron, yielding when necessary, and preventing the 30 action of wind thereon, and it has means whereby the upper end of the entire elevator may be raised or lowered or held at any desired height.

It is my purpose to produce a cheap and 35 serviceable article of this character which can be sold to the farmer and by him applied to a standard make of binding machine.

The following specification sets forth one 40 successful embodiment of the idea, reference being had to the drawings in which:

Figure 1 is a perspective view of this 45 device complete, indicating in dotted lines a power chain applied to its driving sprocket and a rope attached to its bail.

Figure 2 is a cross section on the line 2—2 of Figure 1.

Figure 3 is a longitudinal section.

The frame of this elevator includes rather 50 wide upright sides 1 connected by a bottom board 2 at their lower ends and by a wider bottom board 3 at their upper ends, and the upper edges of the side boards are 55 preferably also connected by straps 4 at their upper and lower ends. A roller 5 has trunnions 6 journaled in bearings at the lower

ends of the sides, and one of said trunnions has a sprocket wheel 7 to which a power chain may be applied as seen in dotted lines. A similar roller has its trunnions 8 journaled in the side boards near their upper ends. Around these rollers moves 60 an endless canvas belt or apron 9 having slats 10 secured across its outer face at intervals, and the chain and sprocket will cause the upper stretch of this apron to move upward between the sides, which latter will 65 prevent a lateral blast of wind from striking the grain which lies on the elevator.

Supported at 20 in the side boards near their lower ends is a rockable cross bar 21 carrying a series of retainer bars 22 extending longitudinally within the frame and standing parallel with and rather close to each other, and the upper ends of these retainer bars are supported by a notched bar or comb 23 whose back 24 extends across 75 between the side boards near their upper ends and whose teeth which are flattened at their lower ends, are spaced to correspond with the spacing of the retainer bars and have the upper ends of said retainer bars attached thereto, leaving the spaces between the teeth alining with the spaces between the retainer bars. At each end of the comb is attached a flexible element such as a strap 25 which leads over the upper edge of a side 80 board and is secured to the outer side of the same as at 26. These straps prevent the comb from falling to such a distance as to permit the upper ends of the slats to stand 85 undesirably close to the cross slats on the apron, while at the same time the straps permit the comb and the upper ends of the retainer bars to rise collectively to a considerable height. The upper edges of the side boards 1 may also be connected 90 by crossed braces 27. Transverse braces or strips 28 are secured across the outer faces of the boards 1 near their ends, and to the upper pair of strips at 29 are pivoted the 95 ends of a bail 30 to which a rope is attached, as shown in dotted lines in Figure 1, the same serving as means for adjusting the upper end of the elevator to any desired 100 position and holding it there.

In applying this device to an ordinary 105 binding machine, the binding parts of the latter are removed and the elevator attached,

its sprocket being connected with the same chain that drives the lower elevator on said machine. The upper end of the elevator is now adjusted so as to lead to the header box, 5 The grain cut by the machine is delivered to the lower end of the elevator and onto its apron or belt beneath the retainer bars 22, and the apron carries or elevates the grain and delivers it to said box. In its passage 10 upward on the upper stretch of the apron, it is held thereon by the retainer bars and moves beneath them, and any pieces of grain which project between the retainer bars will move through the spaces between the comb 15 teeth. The weight of the comb added to that of the upper ends of the retainer bars holds the latter down onto the grain and the grain down on the apron, but the flexible connection or straps 25 permit the comb 20 and retainer bars to rise in case the accumulation of grain is sufficient, and thus the choking or clogging of the elevator at its outlet end is prevented. The opening at the bottom between the bottom boards 2 and 3 25 permits the dropping out of whatever is carried over the upper roller by the apron, and thus the choking and clogging of the lower stretch of the elevator is prevented. While my invention is primarily intended 30 for a use such as has been described, I do not wish to be limited to that particular use. Also, while I have described and shown a

canvas apron with cross slats, I claim no novelty for this detail.

What is claimed is:

A binder elevator including a frame, an endless belt mounted in the frame, a transverse bar rotatably mounted in the sides of the lower portion of the frame for rocking movement, a transverse bar extending between the sides of the upper end of the frame, flexible straps secured to the ends of the last-named bar and to the sides of the frame to permit the bar to rise and fall under the influence of material passing 45 thereunder and to maintain said bar in spaced relation with respect to and above said belt, the lower portion of the upper bar being formed with a longitudinal series of depending teeth each having its lower end 50 flattened, and retainer bars extending longitudinally of the frame and over the endless belt with their upper ends secured to the said flattened ends of the teeth of the upper bar and their lower ends secured to the lower 55 face of the rocking bar for rocking movement therewith.

In testimony whereof, I affix my signature, in the presence of two witnesses.

BERNARD M. MCFARLANE.
